CENTRALIZED TRAFFIC CONTROLLING
SYSTEM FOR RAILROADSCharles S. Bushnell, Rochester, N. Y., assignor to
General Railway Signal Company, Rochester,
N. Y.

Application January 2, 1932, Serial No. 584,428

44 Claims. (Cl. 246—3)

This invention relates to centralized traffic control systems for railroads and more particularly to a means for communicating between a central control point and various points along the railroad whereby an operator can govern traffic controlling devices in the system and can receive indications of the operated position of such traffic controlling devices as well as the progress of trains throughout the particular territory of the system.

In a centralized traffic control system, an operator at a central control point is able to govern traffic movements throughout the territory of the system by supervising the operation of traffic controlling devices thereof. Power operated track switches are usually employed with local approach locking and like means to prevent the movement of these switches in case the operator directs a movement of the switch at a time when traffic conditions make such a switch movement unsafe. The signals, in such a system, are likewise automatically controlled in accordance with local conditions such as the location of trains and the position of switches, yet these signals are under the supervision of the operator inasmuch as he can hold them at stop regardless of their automatic control or he can allow them to clear if their automatic control allows such a clear indication.

The present invention relates to such a system which involves the features of an automatic block system, such as disclosed for example in the application of S. N. Wight, Ser. No. 120,423, filed July 3, 1926, together with a communicating system which enables the operator to supervise train movements by conditioning switches and signals and thus eliminate the use of train orders. The features of the present invention reside more particularly in the communication means that is, the means by which the operator can, at will, select and control a particular traffic controlling device and also the means by which any change in condition of traffic controlling devices or position of trains on the system may distinctively register itself at the control point.

In the communication system of this invention, such traffic controlling devices and circuits which are closely associated may be grouped together to constitute the equipment of a field station. Such a field station may include means suitable for governing the operation of a track switch and associated signals and for indicating the position of the switch, conditions of the signals, the condition of track circuits or such associated

controls and indications as may be desirable in the particular application.

The transmission of controls to the several field stations in the proposed communicating system is accomplished over a single circuit extending to all such field stations of the system and the selection of a particular field station is accomplished by allotting a distinctive code call to each station and impulsing the aforesaid circuit with a particular code call effective to select 10 the corresponding station. The field stations may in a similar manner distinctively register themselves at the control point, one at a time, by impulsing the same circuit with the distinctive code calls allotted thereto.

After the selection of such a field station, a continuation of the coded impulses transmits the selected controls to the selected field station and likewise after a field station registers itself at the control point, a continuation of the coded 20 impulses transmits the indications of that field station to associated apparatus at the control point.

The present invention also proposes to provide distinctive coding means by periodically energizing the aforesaid single circuit with a choice of two distinctive impulses of energy, such impulses being distinguishable by the degree of energization thereof.

A further object of the present invention is to 30 provide a communicating system with a single communicating circuit as above mentioned normally energized from a single source of energy at the central control point with a relatively low value of current, which communicating system 35 may be initiated into operation from the control point by momentarily energizing this communicating circuit with a higher value of current.

A still further object of the invention is to 40 enable any field station to initiate operation of the communication system by opening this circuit thereby locking out all other field stations until completion of this operation with provision against simultaneous initiation of the communication system by several stations by granting 45 superiority to the field stations in accordance with their location relative to the control point.

Other objects, purposes and characteristic features of the present invention will appear as the description thereof progresses, during which 50 reference will be made to the accompanying drawings, in which similar parts throughout the several views are designated by like reference characters provided with distinctive exponents, and in which:—

Fig. 1 shows the apparatus and circuits for a control office in accordance with this invention.

Fig. 2 shows the apparatus and circuits for a typical field station having a distinctive code 5 call.

Fig. 3 shows the arrangement of the line circuit of the present invention.

The system illustrated in the accompanying drawings has been shown in as simple and diagrammatic manner as possible in order to clearly explain the principles and operations thereof without attempting to show the particular arrangement preferably employed in practice.

All functions of the present system are performed by relays which are shown with their wire connections in a conventional diagrammatic manner and symbols are used to indicate sources of energy instead of extending all wire connections to the actual energy sources except the single source of energy for the communicating circuit which is indicated as a battery B. These relays may be of the telephone type and certain ones, it will be noticed, are of the polarized magnetic stick type which remain in either of their operated positions; while the majority of the relays employed are of the neutral tractive armature type. Some of such neutral relays have two independent windings and others have slow acting characteristics which are indicated by having heavy base lines.

The general system layout is shown in Fig. 3 and consists essentially of a single two wire circuit originating and energized at a central point or control office and extending to all field stations of the system, which circuit is normally completed by connecting together the two line wires at the last station. A neutral relay LH which responds only to a high degree of energization and a second neutral relay LL which responds to either a high or a low degree of energization are included in series with the line circuit at each field station as well as at the control office. In other words, the relay LL may be provided with a greater number of turns on its operating winding than relay LH and this ratio of turns will substantially be determined by the ratio of the current of a high impulse to that of a low impulse.

A resistor R¹ at the control office is arranged to limit the energization of the line to a low degree when the system is not in operation or during a period of blank. This resistor R¹ is disconnected during operation by a contact of a relay ST which then makes the degree of energization of the line selectable by a second resistor R² which is shunted by a contact of a relay SEL except when the control office is calling a station at which time it may be either shunted or uncovered by a contact of a code selecting relay CS to determine the degree of energization of each line impulse. A pulsing relay P is also included at the control office and is arranged to periodically energize the line during operation as will be more fully described hereinafter.

Each field station has a relay LO arranged to interrupt the line at a point in the circuit beyond the two series line relays LH and LL of that station whenever that field station is transmitting indications to the control office, thereby locking out such other stations as may be located more remotely with respect to the control office.

The relay LO in addition to breaking the line circuit beyond any field station also completes the line from that station to the control office

by shunting the line wires at that station. This shunt at each station includes a front contact of an SA relay and a resistance RF. This resistor RF may be shunted or uncovered by a contact of a local code selecting relay CS to select the degree of energization of the line impulses in accordance with the codes to be transmitted. A line voltage adjusting resistor RA is included at each field station in the shunt completed on the line at that station by the picking up of the LO relay. The function of these resistors is to equalize the voltage on the series line relays of the circuit for the various field stations inasmuch as the lengths of the included line circuit varies according to the location of the communicating station from the control office. This line circuit arrangement is identical for each station of the system and, as shown in Fig. 3, the line wires are connected together at the last station.

Control office equipment.—The control office equipment includes such conventional manually operable means corresponding to each field station as will enable an operator to set up distinctive conditions therewith, which conditions may be effective to control various traffic controlling devices at the particular field station. The office equipment also includes such indicating means, preferably associated with a miniature track diagram, as will convey information concerning the operated positions of traffic controlling devices and the occupied or unoccupied condition of various track sections in the system. All these controls may be arranged in any convenient manner which will insure the most efficient control of traffic throughout the system. In this disclosure no attempt has been made to show all such parts and their arrangements, but suitable manual controls for a single field station have been shown diagrammatically as typical of other traffic controlling devices.

These controls, as shown in Fig. 1, may be such as control lever SML which is operable to two distinct positions to operate suitable contacts which set up controls for a single track switch. A signal control lever SGL is similarly shown and may be movable to any one of three positions and is for the control of the signals and traffic direction over the single track switch.

The means for displaying the above mentioned indications may be small lights, such as lamp I in Fig. 1, which is shown as indicating the occupancy of a track section and similar means may be arranged for other desirable indications. The control levers as well as the indicating means are preferably associated with a miniature track diagram of the system.

A storing relay SR and a code determining relay CD, one of each for each field station, are included at the control office which are selectively energized to condition the control office for transmitting the station selecting and control codes. The control of the storing relays SR and the interlocking of the CD relays is contemplated to be the same as similar relays fully described in the prior application of W. D. Hailes and D. F. DeLong, Ser. No. 526,674, filed March 31, 1931 and consequently will not be fully described herein.

A bank of station registering relays is included at the control office and consists of pilot relays PT³ and PT⁴ and station registering relays C¹, C² and C³, there being one station registering relay for each field station. For the purpose of storing incoming indications a bank of magnetic

stick relays IN, IN¹ and IN² are employed which are arranged to control the indications of the above mentioned indicating means.

The embodiment of the invention shown here-
5 in utilizes the first two impulses for the station selection and registration so only two pilot relays PT³ and PT⁴ are used which are energized in accordance with the code call of the incoming field station. These two pilot relays make possible 10 the registration, at one time, of any one of three different field stations by selectively energizing either relay C¹, C² or C³. It is obvious that with two impulses four different codes are obtainable but for reasons later described only 15 three stations are selected. Also, it is obvious that any number of stations may be selected by employing the proper number of impulses or steps, but to simplify the disclosure only three stations are considered. After the selection of 20 one of the relays the remaining impulses of the cycle, as previously described, are utilized to transmit the indications to the indication storing means associated with that station.

A suitable number of stepping relays are also 25 included and arranged to be energized sequentially, one at a time, by impulses applied to the line circuit. The number in the present embodiment is illustrated as five stepping relays a, b, c, d and e, two of which are employed for station 30 selection and registration and the other three for transmission of controls and indications.

The impulsive relay P, which as previously 35 mentioned functions to periodically energize the line circuit, is arranged in combination with the stepping relay bank to be selectively energized thereby. Also, associated with the stepping relay bank is a half step relay SP arranged, as later described, to energize the relays of the stepping bank one at a time in response to their impulses.

40 A slow acting cycle demarcating relay SA, a starting and stopping relay ST, a slow acting repeating relay STP, and a selecting relay SEL are also included at the control office. The code of each step is determined, as previously mentioned, by the relay CS which is energized by contacts of the stepping bank according to the station selecting code and controls which are selected to be transmitted.

45 *Field station equipment.*—The grouping of various traffic controlling devices into field stations is determined by the particular arrangement and location of such devices but as illustrated in the field station equipment of Fig. 2, a group will be considered as a single track switch TS power 50 operated by a switch machine SM with signals SE¹ and SE² governing movements in one direction and signals SW¹ and SW² governing movements in the other direction thereover. The apparatus and circuits necessary to establish communication between a field station and the control office is the same for each station, the only 55 difference being that certain distinctive connections are made at each station to render it responsive to a particular code call assigned thereto.

The station selecting apparatus for the field stations is similar to that of the control office except that, inasmuch as the line circuit is intermittently energized at the control office by the pulsing relay P a similar relay is not necessary at the field station. A slow acting relay SAP is included to repeat the position of the relay SA which then functions in a stick circuit of the relay LO as will be later described. The same 70 number of stepping relays are employed at the

field stations as at the control office, said relays at the field station being identified as 1, 2, 3, 4, and 5 in Fig. 2, and obviously this number is determined by the number of stations and the number of indications or controls to be transmitted as mentioned in connection with the control office equipment. These stepping relays are energized sequentially one at a time in synchronism with the stepping relays at the control office and similar pilot relays PT¹ and PT² are arranged 10 to be selectively energized or de-energized respectively by the character of the first two impulses. Through these relays a station may be selected and the circuit completed through their contacts to respectively position function 15 relays SMR, SG and DR by the character of the remaining impulses of the cycle. The function relay SMR is of the two-position polarized type and is employed to control a switch machine SM, such as disclosed for example, in the patent to 20 W. K. Howe, Patent No. 1,466,903 dated September 4, 1923 which is also subject to conventional detector locking and approach locking means such as disclosed in Patent No. 2,038,463 granted April 21, 1936 which thus prevents unsafe operation of the switch points. The function relay SG is arranged to allow the signals at this station to be cleared or cause them to be held at stop, while the position of the function relay DR selects the direction of traffic by clearing the 30 proper signals for the route selected by the track switch.

The field station equipment also includes a change relay CH and a change storing relay CHS which relays are arranged to register the existence of any new indications to be transmitted to the control office. These new indications are determined by contacts distinctively actuated in accordance with local conditions which were previously mentioned. The various relays, wire 40 connections and other apparatus of each field station may be arranged in a unit cabinet which cabinet, because of the similarity of all field station equipment as well as the control office equipment, may be constructed as an interchangeable unit to which suitable jumpers and external connections are added to individually adapt it to its particular part in the system. Various other auxiliary equipment such as wire terminals, lightning protective means and other necessary equipment which is customary in railway signalling practice are also included at both the control office and field stations but have been omitted to simplify this disclosure.

55 *Operation of the system.*—It is believed that the characteristics and functions of the present system can best be pointed out by further discussion of the various operations through which the system functions under the different conditions. The line circuit, as briefly described, when the 60 system is at rest or in a period of blank, is energized to a low degree of energization and the position of the relays of the system at such time is as shown in the accompanying drawings. The initiation of operation of this system to transmit 65 new controls from the control office may be accomplished by the movement of any control lever, or operation may be automatically initiated at any field station having new indications to transmit to the control office, but in either case the 70 system operates through what is termed an operating cycle and then returns to its normal at rest condition, as shown.

75 Each of such operating cycles of the system consists of a plurality of coded impulses always 75

of the same number and divided into two parts conveniently termed a selecting or registering part and a transmitting or communicating part. In the case of a control office call the first part of the cycle selects the particular field station with which communication is to be held and the second part is the actual communication which in the case shown, is the transmission of new controls to the selected station. In a similar manner, the field station cycle registers the station itself at the control office on the first part of the cycle and transmits its new indications on the remaining part of the cycle.

In describing the operation of the system in detail it is convenient to discuss the several groups of operations individually under separate headings, first explaining the transmission of controls from the control office and second the means for the communication of new indications from the field stations and finally the operation of the system to lock out all but one field station when more than one of such stations have new indications to transmit.

Manual starting.—When the system is at rest, the operator may start the transmission of controls to any field station by moving the control lever of such a traffic controlling device as he may desire to operate. In the particular embodiment shown in Fig. 1, it is obvious that the movement of either control lever SML or SGL from one position to another momentarily opens the stick circuit for the storing relay SR¹ which is thereby caused to assume a de-energized position. This stick circuit may be traced from (+), contact 6 of lever SGL in any extreme position, either wire 1 or 8, contact 9 of lever SML in either position, wire 10, front contact 11 of relay SR¹, wire 12, relay SR¹, to (—).

The energizing circuit for the storing relays SR and the means in which the de-energizing of the storing relays of the system is effective to energize corresponding code determining relays CD is not shown in this disclosure but may be clearly understood by referring to the prior application of W. D. Hailes and D. F. DeLong Ser. No. 526,674, filed March 31, 1931 which clearly shows and describes the arrangement which is proposed to be used in this system.

However it may be stated that the code determining relays CD of the system are connected to permit their energization only when the system is at rest and are so interlocked to enable the energization of only one at a particular time in an order which may be arranged in any manner which is found desirable. A stick circuit is arranged to hold these CD relays up until the completion of the cycle of operation which they initiate or until the picking up of the last stepping relay e. A storing relay SR may be said to be arranged so as to register, by de-energization thereof, a change in position of any or all the control levers associated therewith and also to store such change until, in proper order, the operation of the system to transmit these controls has taken place.

Considering now that for some time only the present new position of controls has been set up, the relay CD¹ is energized as previously mentioned and inasmuch as the system is at rest at this time, the energization of the relay CD¹ energizes the starting relay ST over a circuit from (+), front contact 13 of relay CD¹, wire 14, relay ST, to (—). The picking up of relay CD¹ also completes a circuit to pick up the selecting relay SEL from (+), front contact 206 of relay CD¹,

wire 207, relay SEL, wire 208, back contact 209 of relay SA to (—).

The line circuit is normally energized, before the picking up of relay ST, to a low degree of energization from the battery B, wires 17 and 18, resistor R¹, wire 15, back contact 16 of relay SA, wire 21, back contact 19 of relay ST, wire 20, line relay LH, wire 21, line relay LL, wire 22, back contact 23 of relay P, line wire 24, through the several field stations and returning by line wire 10 25 to battery B. However, the energization of relay ST moves contact 19 of relay ST which is shown as the conventional make-before-break type and thereby does not interrupt the line circuit in moving to a new position but serves 15 only to cut out the resistor R¹ and energize the line to a high degree of energization over a circuit from battery B, wires 17, 65, 66, 67 and 68, front contact 69 of relay STP, wires 70 and 73, front contact 19 of relay ST, wire 20, relay LH, 20 wire 21, relay LL, wire 22, back contact 23 of relay P, line wire 24 and returning by line wire 25 to battery B. This high degree of energization is of a duration determined by the dropping of the slow acting relay STP which opens the line circuit at its front contact 69 in as much as this relay STP is de-energized at the back contact 26 of relay ST energized.

The de-energization of the line circuit drops the relay LL which energizes the slow acting relay SA through the back contact 28, but the slow acting characteristics of this relay SA allows the first stepping relay a to pick up and the code selecting relay CS to be conditioned before the armature of the relay SA actually picks up. 30 When the armature of relay SA does pick up, the line circuit is again energized for the first impulse as follows:—from battery B, wires 17 and 65, resistor R² either shunted or unshunted by the back contact 11 of relay CS, wires 72 and 77, front contact 74 of relay SA, wires 75 and 73, front contact 19 of relay ST, wire 20, relay LH, wire 21, relay LL, wire 22, back contact 23 of relay P, line wire 24 and returning by line wire 25 to battery B. 40

The circuits effective to pick up the stepping relay a and to condition the code selecting relay CS will later be described in connection with the explanation of the stepping relays and in connection with the explanation of the selection of 50 the degree of energization of impulses.

When the relay SA picks up, the following circuit from (+), back contact 29 of the last stepping relay e, wires 30 and 31, front contact 32 of relay SA, wire 33, front contact 34 of relay ST, wire 35, holding winding of relay ST, to (—), is completed which holds up the relay ST until the completion of the operating cycle at which time it is dropped as later described. A stick circuit for relay SEL is also completed by the picking up of relay SA through its front contact 88 which is arranged to complete this stick circuit before the pick-up circuit for relay SEL is broken at the back contact 209. It may be said that the function of relay SEL is to prevent 65 a code call originating at the control office from conditioning the station registering bank of relays at the control office by interrupting the code responsive circuit at its back contact 210 in as much as this relay SEL may be energized only 70 during an operating cycle initiated by the control office.

It will also be mentioned here that relay SA is provided with sufficiently slow acting characteristics to enable its armature to remain up 75

during successive line impulses and only allowing this armature to drop at the end of the cycle of such impulses and thus defines or demarcates the cycle.

5 The dropping of the line relay LL starts the impulsing means for the line as previously mentioned but before describing in detail this impulsing means it is considered expedient to describe how the degree of energization of impulses is selected to provide distinctive codes.

10 *The selection of the degree of energization of impulses.*—The present system provides a means for coding the line impulses by selectively shunting or uncovering a series line resistor thereby determining the degree of energization of impulses. In other words, an impulse of a high degree of energization may be placed on the line circuit which is effective to operate both relays LH and LL of the system, this being accomplished by 15 shunting the resistor R²; or an impulse of a low degree may be placed on the line circuit which is effective to operate only relay LL of the system by removing the shunt on the resistor R².

20 The selective shunting of this resistor is accomplished by energizing or de-energizing a code selecting relay CS for each impulse of the line. The condition of the code selecting relay CS is determined in the first part or station selecting impulses of the cycle by the particular code determining relay CD which is energized and each code determining relay CD is arranged to energize the code busses 36 and 37 in a manner to pick up or drop the code selecting relay CS according to the position of the jumpers 38 and 39, 25 which positions are different for different CD relays. The circuit effective to condition the code selecting relay CS is shifted from one of these code busses to the other by the picking up of corresponding stepping relays.

30 It should also be understood that this simple arrangement consisting of only two impulses for station selecting is capable of selecting only three stations and that additional impulses may be employed to select any number of stations obviously 35 requiring additional code busses arranged with distinctive jumper connections as typically illustrated by the busses 36 and 37 shown herein. After the last station selecting impulse, which in Fig. 1 is the second impulse, the control of the code selecting relay CS is placed on the busses 40, 41, and 42 respectively to select the energization of the remaining three impulses of the cycle. These busses 40, 41, and 42 are energized also 40 by the particular CD relay which is energized and the polarity of such energization is determined by the position of the control levers SML and SGL thus determining the code of the remaining impulses.

45 In the present system, the conditioning of the code selecting relay CS is performed on the de-energized period of the line, which condition is maintained throughout the succeeding energized period. The relay CS is constructed to operate slightly slower than the stepping relays and consequently upon the first de-energization of the line, as described in connection with the manual starting operation, the first stepping relay a picks up over a circuit to be traced later before the code selecting relay CS is conditioned. With the relay 50 CD¹ energized, the relay CS is conditioned on the first de-energized period of the line over the following circuit from (+), jumper 38, front contact 45 of relay CD¹ wire 46, first station selecting bus 36, front contact 47 of stepping relay a, wire 48, back contact 49 of stepping relay b, wire 50, back

55 contact 51 of relay c, wire 52, back contact 53 of relay d, wire 54, back contact 55 of relay e, wire 56, back contact 57 of relay LL, wire 58, operating winding of relay CS to a neutral polarity of energy N.

60 It is now obvious that the relay CS is energized to open the shunt on the resistor R² at its back contact 71 and select a low degree of current for the first impulse, and this relay CS is held up through a circuit including its front contact 59. 10 This first de-energized period is marked off by the picking up of the relay SA as previously described. However, on the second de-energized period following the first impulse, the second stepping relay b is picked up and the following 15 circuit is completed for positioning the relay CS from (-), front contact 60 of relay CS, wires 61 and 62, jumper connection 39, front contact 63 of relay CD¹, wire 64, the second code bus 37, front contact 49 of relay b, wire 50, back contact 51 of 20 relay c, wire 52, back contact 53 of relay d, wire 54, back contact 55 of relay e, wire 56, back contact 57 of relay LL, wire 58, operating winding of relay CS to a neutral polarity of energy N. It is obvious that the completion of this circuit 25 causes current to flow in the reverse direction in the operating coil of relay CS thus bucking the effect of the holding current in the stick circuit and effecting the dropping of the armature of the relay CS which breaks the last traced circuit at 30 its front contact 60 thus interrupting the circuit before the armature can again pick up and resulting in maintaining a de-energized condition of the relay CS.

35 The second impulse is then made of a relatively higher degree of current in or voltage across the line because the resistor R² is shunted by the back contact 71 of relay CS and thus it can be seen that the coding of each impulse is executed after the picking up of an associated stepping relay on 40 the de-energized period preceding such impulses in accordance with the code which is selected. In other words, before the first impulse the picking up of relay a connects relay CS to buss 36, before 45 the second impulse the picking up of relay b connects it to buss 37, before the third the picking up of relay c connects it to buss 40, and so on throughout the entire cycle of impulses. Now, keeping in mind this method of determining the degree of energization of impulses, a brief description will be given to the method of applying such impulses to the line at the proper time space interval and to the method of sequentially 50 energizing the relays of the stepping bank of successive impulses.

55 *Impulsing means and operation of the stepping relays.*—The impulsing means of the present system is arranged to apply energy of a preselected degree to the line circuit for a predetermined time interval termed a conditioning period and 60 then de-energize the line circuit for another predetermined interval termed an execution period. Operation of the system is initiated in a different manner at a field station than at the control office, as will be later described, but regardless of 65 where operation is initiated the starting of an impulsing cycle is always marked by a long de-energized period of the line the end of which period is demarcated by the energization of the slow acting relays SA of the system previously 70 mentioned.

Upon the first de-energization of the line circuit the first stepping relay a is energized as follows:—from (+), back contact 79 of relay LL, wire 80, back contact 81 of relay SP, wire 82, back

contact 83 of relay *d*, wire 84, back contact 85 of relay *b*, wires 86 and 87, through windings of relay *a* to (—). The stick circuit for the stepping relays is also completed as soon as the relay SA 5 picks up from (+), front contact 88 of relay SA, wires 89, 90, and 91 to the stick contacts of the stepping relays.

The relay SA and the line circuit being now energized as previously mentioned, the picking up 10 of the first stepping relay *a* energizes the half step relay SP as follows:—from (+), front contact 93 of relay *a*, wire 94, back contact 95 of relay *b*, wire 96, back contact 97 of relay *c*, wire 98, back contact 99 of relay *d*, wire 100, back contact 101 of relay *e*, wire 102, operating winding of relay SP, wire 103, front contact 104 of relay LL, wire 105, front contact 106 of relay SA to neutral polarity of energy (N). Relay SP is held up from (+), front contact 88 of relay SA, 15 wires 89 and 90, front contact 109 of relay SP, wire 110, holding winding of relay SP to (—).

The relay SP picking up completes the following circuit to pick up the pulsating relay P from (+), front contact 111 of relay SA, wire 112, front 20 contact 113 of relay SP, upper winding of relay P, wire 114, front contact 115 of relay *a*, wire 116, back contact 117 of relay *b*, wire 118, back contact 119 of relay *c*, wire 120, back contact 121 of relay *d*, wire 122, back contact 123 of relay *e* 25 to (—). Thus, the line circuit is de-energized by opening the circuit at back contact 23 of relay P and the first conditioning period is completed and the next execution period is begun by dropping of the line relay LL and completing an energizing circuit for the second stepping relay *b* as follows:—from (+), back contact 79 of relay LL, wire 80, front contact 81 of relay SP, wire 125, back contact 126 of relay *e*, wire 127, back contact 128 of relay *c*, wire 129, front contact 130 of 30 relay *a*, wire 131, windings of relay *b* to (—).

With the relay *b* up, the energizing circuit for relay P is broken at the back contact 117 of relay *b*, and the line circuit is again energized on the second impulse through the back contact 23 of 45 relay P. The relay SP is now dropped by reversing the current thereon over a circuit from (—), front contact 132 of relay SP, wires 133 and 134, front contact 95 of relay *b*, wire 96, back contact 97 of relay *c*, wire 98, back contact 99 of relay *d*, 50 wire 100, back contact 101 of relay *e*, wire 102, operating winding of relay SP, wire 103, front contact 104 of relay LL, wire 105, front contact 106 of relay SA to the neutral potential (N). This circuit is arranged as the circuit previously described to drop relay CS by neutralization of currents and so that its own contact 132 interrupts the current in the reversed polarity circuit and its own contact 109 opens the normal polarity circuit before such energy can be effective to again pick 55 up the armature.

The dropping of the relay SP now again energizes the pulsing relay P over a circuit from (+), front contact 111 of relay SA, wire 112, back contact 113 of relay SP, lower winding of relay P, 60 wires 136 and 137, front contact 117 of relay *b*, wire 118, back contact 119 of relay *c*, wire 120, back contact 121 of relay *d*, wire 122, back contact 123 of relay *e* to (—). Thus the line is successively energized and de-energized through the 65 cycle by the picking up and dropping of the pulsing relay P and the stepping relays are successively energized one at a time by alternately picking up and dropping of relay SP.

70 75 *Station selection.*—The selection of a particular

field station during a control office call is performed as above pointed out during the first part of the operating cycle in accordance with the coding of the impulses. Irrespective of the code of the impulses each impulse causes the step-by-step means at the control office and at each field station to take one step and the degree of energization of each impulse is arranged to condition a pilot relay associated with that step, thereby selecting one station and rendering all others unaffected by the remaining coded impulses of the cycle.

In the code employed in this system a choice of a high or a low degree of energization of each impulse gives four different code calls for two 15 steps or impulses, eight different code calls for three impulses and so on, each additional step or impulse doubling the number of possible different code calls. A code table such as the following may be arranged with the present system 20 by employing two steps thus providing four different code calls.

Typical code table

Code call	First step	Second step
1	High energization	High energization
2	High energization	Low energization
3	Low energization	High energization
4	Low energization	Low energization

It was previously described in connection with the selection of the degree of energization of impulses that the first two impulses transmitted from the control office when the relay CD¹ is 35 energized presents a low degree of energization on the first step and a high degree on the second step. This code call happens to be the one assigned to the field station shown in Fig. 2 and the way in which it is effective to select the station 40 will now be considered.

It was previously mentioned that the beginning of the operating cycle is always marked by a de-energized period of the line which is sufficiently long for the slow acting relay SA at 45 the control office to pick up and this period is effective at each field station to also pick up the SA relay of such field station over a circuit completed at the back contact 107 of relay LL¹ for the station shown in Fig. 2. This de-energized 50 period also completes a circuit to start the stepping bank of relays by energizing the first stepping relay 1 in Fig. 2 from (+), back contact 139 of relay LL¹, wire 140, front contact 141 of relay SA¹, wire 142, back contact 143 of relay SP¹, wire 144, back contact 145 of relay 55 4, wire 146, back contact 147 of relay 2, wire 148, windings of relay 1 to (—). A stick circuit for the stepping relay is also completed from (+), front contact 149 of relay SA¹, wires 150, 151 and 152, 60 to the stick contacts of the stepping relays.

These stepping relays 1, 2, 3, 4, and 5 are sequentially energized one at a time in the same manner as described in connection with the stepping relays of the control office and the same arrangement is used at each field station of the system.

Inasmuch as the first impulse of the operating cycle under consideration is of a low degree of energization, the relay LH¹ being responsive 70 only to a higher degree of energization is not picked up, thus completing a de-energized circuit for the windings of the pilot relay PT¹ as follows:—from (—), back contact 155 of relay LH¹, wire 156, front contact 157 of relay LL¹, wire 75

158, front contact 159 of relay SA¹, wire 160, back contact 161 of relay LO, wire 162, back contact 163 of stepping relay 2, wire 164, front contact 165 of stepping relay 1, wire 166, through 5 the operating winding of relay PT¹, to negative (—).

This circuit leaves the first pilot relay PT¹ in its de-energized position as shown but when the next stepping relay 2 is energized the second impulse 10 is of a high degree of energization and the relay LH¹ is picked up thereby completing an energizing circuit for the second pilot relay PT² from (+), front contact 155 of relay LH¹, wire 156, front contact 157 of relay LL¹, wire 158, front contact 159 of relay SA¹, wire 160, back contact 161 of relay LO, wire 162, front contact 163 of relay 2, wire 167, through the operating winding of relay PT², to (—). A stick circuit for 15 these pilot relays may be completed from (+), front contact 149 of relay SA¹, wires 150 and 168, to the stick contacts of each pilot relay, which stick circuit for a picked up pilot relay is completed for the remainder of the operating cycle.

Thus, on the first two steps of the operating 20 cycle under consideration, the first pilot relay PT¹ remains de-energized and the second pilot relay PT² is energized at each field station, but it is obvious that a circuit through the contacts of these pilot relays is completed at one station 25 only inasmuch as the jumper connection 169 is in a different position at each field station. As previously mentioned, the jumper connection 169 at the field station in Fig. 2 is so positioned to render it responsive to the code call previously 30 considered and consequently with the pilot relays thus positioned a circuit which enables the remaining coded impulses of the cycle to position the function relays at this station only is completed as follows:—from (+) or (—) as determined by the position of the relay LH¹, contact 35 155, wire 156, front contact 157 of relay LL¹, wire 158, front contact 159 of relay SA¹, wire 160, back contact 161 of relay LO, wire 170, jumper connection 169, back contact 171 of pilot relay PT¹, wire 172, front contact 173 of pilot relay PT², wire 174 to the contacts of the remaining three 40 stepping relays whereby the function relays SMR, SG and DR are positioned sequentially in accordance with the code of the remaining three 45 impulses.

The picking up of the last stepping relay e opens the previously traced stick circuit for the cycle starting and stopping relay ST at the back contact 29, but inasmuch as the operating cycle 50 is not complete until after the application of the last impulse on the line, a second stick circuit is provided to hold up the relay ST during this last impulse. It will be noticed that the half step relay SP is de-energized during the 55 energization of the last stepping relay e and again becomes energized on the next energized period of the line because its circuit is completed at front contact 101 of relay e. Therefore a back contact 43 is provided on relay SP to maintain this stick circuit as follows:—from (+), 60 back contact 43 of relay SP, wire 31, front contact 32 of relay SA, wire 33, stick contact 34 of relay ST, wire 35, holding winding of relay ST to (—).

Thus, it will be noted that the line impulse following the energization of the last stepping relay e opens the stick circuit for relay ST at back contact 43 of relay SP but this impulse continues of the same degree of energization as selected 65 by the code selecting relay CS over the following 70

line circuit:—from battery B, wires 17 and 65, resistor R² either shunted or unshunted by back contact 71, wires 72 and 76, front contact 16 of relay SA, wire 27, back contact 19 of relay ST, wire 20, relay LH, wire 21, relay LL, wire 22, 5 back contact 23 of relay P, line wire 24 and returning by line wire 25 to battery B.

This last impulse continues for a sufficient time to drop relay SA by opening its circuit at back contact 28 of line relay LL and the line is again completed through its normal circuit as previously traced. It is evident that the slow acting relays SA at each field station also drop during this last impulse and thereby interrupt the stick circuits for all the pilot relays and 15 stepping relays of the system which return all apparatus to a normal at rest condition.

By analogy to the above traced cycle of operation to transmit controls to the field station it may be readily understood how, by a similar 20 cycle of operation, a field station may register itself at the control office by positioning the pilot relays PT³ and PT⁴ during the first part of the cycle and likewise transmit indications from that station on the remainder of the cycle by positioning indication relays IN, IN¹ and IN². The station registering relays C¹, C² and C³ at the control office are arranged to be selectively energized according to the positioning of the pilot 25 relays PT³ and PT⁴ and are thus effective to connect the indicating buses 176, 177 and 178 to the proper group of indication relays, there being one group of indication relays at the control office associated with each field station of the system. 35

Automatic starting and sequence of communication of station codes.—The above mentioned cycle of operation to transmit indications to the control office may be automatically initiated when the system is at rest by any field station 40 where a change occurs in the occupied or unoccupied condition of the track circuit, the position of the track switch, the indication of the signals, or the like. Such a change momentarily opens the stick circuit of the change relay 45 CH. This arrangement for registering and storing a change in condition at the field station is of the type disclosed in the prior patent to D. F. DeLong et al, No. 1,852,492 granted April 5, 1932, and will not herein be considered in detail. However, it may be stated that the change relay CH and the change storing relay CHS are so arranged that a change in condition at the field station is registered and stored until the system 50 is in condition for an operating cycle to be initiated at that particular station to transmit such new indications to the control office. 55

It is now obvious that upon the dropping of the change relay CH at a time when the system is at rest or when the line is normally energized 60 at a steady low degree of energization, a circuit is completed to pick up the relay LO from (+), back contact 179 of relay LH¹, wire 180, front contact 181 of relay LL¹, wire 182, back contact 183 of relay SA¹, wire 184, through the operating winding of relay LO, wire 185, front contact 186 of the change storing relay CHS to (—). Now referring to Fig. 3 and considering that the field station in Fig. 2 is the first field station of 65 the system shown herein, it is obvious that the picking up of relay LO de-energizes the line circuit of the system beyond the first station because of the open back contact 154 of relay LO and the line circuit from this station to the con- 70

trol office is also open at present by the front contact 187 of relay SA¹.

The relay LO is maintained up during the first de-energized period of the line over a stick circuit from (+), back contact 190 of relay 5, wires 191 and 192, back contact 193 of line relay LL¹, wires 194 and 195, front contact 196 of relay SAP, wire 197, stick contact 198 of relay LO, wire 199, holding winding of relay LO to (-). The contact 193 of relay LL¹ is constructed to make on a back point before contact 181 of the same relay breaks at its front point thereby enabling the dropping of relay LL¹ to complete this stick circuit before the pick-up circuit for this LO relay is broken at the back contact 181.

This first de-energized period of the line also completes a circuit at the control office to pick up the relay ST from (+), back contact 211 of relay LL, wire 212, back contact 213 of relay SA, wire 214, relay ST to (-). It may be stated here that this contact 213 of relay SA is arranged to maintain this circuit until the making of the front contact 32 during the picking up of relay SA.

However, after a predetermined lapse of time all the slow acting relays SA of the system are picked up, such as through the back contact 197 of relay LL¹ at the first station, and the line circuit from the control office over the wire 24 is completed to this station through relay LH¹ and relay LL¹, wire 108, front contact 154 of relay LO, wire 175, front contact 187 of relay SA¹, wire 188 through either the resistor RF or the back contact 189 of relay CS¹ as determined by the transmitted code call, through the resistor RA and returning to the control office by wire 25. To maintain the previously traced stick circuit for the LO relay when the line is energized, a front contact 200 is provided on relay SA¹ which is arranged to shunt the back contact 193 of line relay LL¹ when energized.

During the first impulse the half step relay SP¹ is energized which establishes a shunt around the front contact 196 of relay SAP over wire 201, front contact 202 of relay SP¹, wires 203 and 197. This contact 202 of relay SP¹ is effective to complete the stick circuit for the relay LO until the second stepping relay 2 picks up on the de-energized period following the second impulse and shunts the contact 202 by a front contact 204 of relay 2. This last stick circuit is maintained throughout the remainder of the operating cycle at which time the relay LO is de-energized in the same manner as the relay ST at the control office, that is by interrupting one circuit during the de-energized period preceding the last impulse but providing an auxiliary circuit, such as through the front contact 205 of relay SP¹, which is effective to maintain the relay LO energized until the application of the last impulse.

In the case that a plurality of field stations have new indications to transmit to the control office, preference is granted to a station in respect to its location in the line circuit. This can be understood by noticing that the picking up of the LO relay at the station nearest the control office interrupts the line circuit to other stations more remotely located, thereby preventing subsequent energization of their LO relays because their energizing circuit includes a front contact of the associated LL relay which is necessarily de-energized, and further because the line circuit remains open beyond such nearest station.

It is obvious that a condition may exist where-
75 by a plurality of LO relays may become ener-

gized at the beginning of the same operating cycle, but in such a case the LO relay at the field station nearest the control office will be the only one to remain energized after the first impulse of the cycle. This can be seen by considering 5 the stick circuit of the LO relay effective during the first and succeeding impulses of the cycle as was previously described. The relay SP at the nearest station in this case obviously picks up on the first impulse which maintains the LO relay 10 stick circuit through its front contact 202 and on the next de-energized period of the line the second stepping relay 2 picks up to maintain this circuit throughout the remainder of the cycle. However at more remote stations this first im- 15 pulse does not occur and consequently the above relay operations are not present to maintain their LO relay stick circuits and consequently they are dropped out as soon as their associated SAP relays drop. In any event, no stepping will 20 occur at such remote station, because the line circuit is open at a point toward the control office.

General summary.—The characteristic features, method of operation and advantages of the 25 system as a whole can be readily appreciated from the foregoing explanation of the various individual steps in the operation of the system of this invention; and it is believed that a brief and general description will suffice to make clear 30 the nature of the invention both broadly and specifically.

The communication system of the present invention comprises essentially a two wire circuit energized normally to a comparatively low 35 degree of energization from a source of energy at the control office and extending through each field station of the system. This line circuit, as employed for field station indication purposes, may be shifted by a lock-out relay LO included at 40 each field station to thereby exclude other field stations more remotely located with respect to the control office and at less remote stations such lock-out relay cannot be later picked up, so that it is not possible to energize more than one of 45 these LO relays at a time. A series relay LH is included at each field station and at the control office whereby distinction is made between the code of each impulse inasmuch as this relay is arranged to be responsive to only impulses of the 50 higher current value of the two distinctive choices of impulses.

The impulses of this line circuit regardless of their code are effective to sequentially step a bank of stepping relays in a manner quite well 55 known in the art and similar banks of such relays are included at each field station and at the control office. The generation of such impulses is also done in a conventional manner by energizing and de-energizing a pulsing relay P located 60 at the control office for each impulse thereby opening and closing the line circuit through a contact operated by this pulsing relay.

During a cycle of impulses initiated at the control office, a series line resistor is either 65 shunted or uncovered during the de-energization period of the line preceding such impulse to thereby determine the degree of energization of that impulse in accordance with the code call of the particular field station with which commun- 70 ication is to be held. In a similar manner, the degree of energization of each impulse during a cycle of operation initiated by a field station is determined by shunting or uncovering a resistor introduced into the line circuit by initiation of 75

operation by that station, such, also being in accordance with the code call thereof, whereby it registers itself and its indication at the control office.

5 To prevent mutilation of a code call by the initiation of an operating cycle at a field station at a time when an operating cycle is already started, the system provides an energizing circuit for the starting means or the LO relay at the field station which is incomplete during an operating cycle. Likewise, interference with an existing cycle of operation is prevented at the control office by providing a relay SEL which may be energized to initiate operation only when the system is at rest.

These relays, which are energized only when operation of a cycle is initiated at that location, that is, the relay SEL at the control office and relays LO at the field stations, also function to 20 interrupt the circuits which conditions the local control or indication registering means, thereby preventing the impulses transmitted from each particular location from conditioning its own registering means.

25 Although it has been pointed out that four different code calls are obtainable with two impulses, eight with three, and so on, it is considered expedient in practice not to assign a code call, such as No. 4 in the typical code table shown 30 above, to any field station because the circuits are so arranged that this code call leaves both pilot relays PT¹ and PT² de-energized which condition would obviously be duplicated in this station by a failure of these relays and give an erroneous selection of this station.

Various other characteristic features and advantages of the present invention will be apparent. The specific organization of the relays and circuits is shown and described as merely one 40 illustrative specific embodiment of the invention and it is to be understood that various modifications, adaptations and additions may be made to the specific embodiment without departing from the spirit or scope of the invention, with the appended claims being intended to define the several features and limitations in the scope of the invention rather than the foregoing description.

What I claim is:—

1. In a centralized traffic controlling system for railroads, a control office, a plurality of field stations, a communicating circuit extending from said control office to all of said field stations, means at the control office for placing a plurality of different combinations of distinctive current impulses on said communicating circuit said distinctive current impulses being distinguishable by the degree of current thereof, step-by-step means at said control office and at each field station all operated in synchronism by said distinctive current impulses on said communicating circuit, and station selecting means at said field stations selectively responsive to the different combinations of said distinctive current impulses.

2. In a centralized traffic controlling system for railroads, a control office, a plurality of field stations, a communicating circuit conductively connecting said control office to all of said field stations, impulsive means at said control office arranged to intermittently energize said communicating circuit a predetermined plural number of times in each cycle, means at said control office for selecting the amount of current of each of said communicating circuit impulses according to predetermined codes, and code responsive means 55 at each field station arranged to sensitize only

one field station during a particular combination of impulses to render it responsive to following impulses.

3. In a centralized traffic controlling system for railroads, a control office, a plurality of field stations, a communicating circuit extending from said control office to all of said field stations, impulsive means at said control office arranged to intermittently energize said communicating circuit, registering means at said control office associated with each field station, selecting means at each of said field stations for determining the amount of current of each of said communicating circuit impulses according to predetermined codes, lockout means whereby only said selecting means at one field station can be effective at one time, and code responsive means at said control office arranged to sensitive one of said registering means during a particular combination of impulses to render it responsive to following impulses.

4. In a centralized traffic controlling system for railroads, a control office, a plurality of field stations, a communicating circuit extending from said control office through each of said field stations, traffic controlling devices and control means therefor at each station; means in the control office manually controllable by the operator for applying to this communicating circuit any one of a plurality of differently arranged cycles of impulses which impulses are distinctive by the amount of current thereof, and means at each of said field stations selectively responsive to the arrangement of impulses of the first part of said cycles to render said control means at a particular field station responsive to the remaining impulses of said cycles.

5. In a centralized traffic controlling system for railroads, a control office, a plurality of field stations, a communicating circuit extending from said control office to each of said field stations, pulsing means at said control office arranged to apply a series of current impulses on said communicating circuit, series current limiting means in said communicating circuit at said control office, a selectable shunt circuit for said current limiting means operable to pre-select the degree of current of each of said communicating impulses in accordance with various distinctive code calls, and means at each of said field stations selectively responsive to said code calls.

6. In a centralized traffic controlling system for railroads, a control office, a plurality of field stations, traffic controlling devices at each station having different operated conditions, a communicating circuit extending from said control office to each of said field stations, means for transmitting from said control office over said communicating circuit different combinations of impulses distinctive by their amount of current for governing the operated conditions of said traffic controlling devices, and means for transmitting from any field station over said communicating circuit different combinations of impulses distinctive by their amount of current for indicating at the control office the operated conditions of traffic controlling devices at that station.

7. In a centralized traffic controlling system for railroads, a control office, a plurality of field stations, a communicating circuit extending from said control office to said field stations, means at said control office for applying a series of impulses to said communicating circuit, impulse selecting means at said control office for deter-

- mining the amount of current of each impulse to thereby establish different combinations, each combination being a characteristic code call for one of said stations and the controls for that station, impulse selecting means at each field station for determining the amount of current of each impulse to establish different combinations in accordance with the distinctive code call of that station and the indications to be transmitted from it to the control office, and lock-out means whereby only one of said impulse selecting means at a field station or at the control office can be effective at one time.
8. In a centralized traffic controlling system for railroads, a control office, a plurality of field stations, a communicating circuit extending from said control office to said field stations, means at said control office for applying a series of impulses to said communicating circuit, manual initiating means at said control office for said impulse applying means, automatic initiating means at each field station for said impulse applying means, and impulse selecting means at said control office and each field station operable to determine the degree of current strength of each of said impulses, said impulse selecting means being effective only when the associated initiating means initiates operation of said impulse applying means.
9. In a centralized traffic controlling system for railroads including a control office, a plurality of field stations and step-by-step mechanisms at said control office arranged to be initiated into operation at the control office or at the field stations, a communication circuit normally extending from said control office to each of said field stations, means at each field station for shifting said communicating circuit to exclude more remote stations by the initiation of operation of said step-by-step mechanism at that station, and means at each field station for applying different combinations of distinctive current impulses on said communicating circuit when operation is initiated at that field station said distinctive current impulses being distinguishable by the degree of current strength thereof.
10. In a centralized traffic controlling system for railroads, a control office, a plurality of field stations, a communicating circuit normally connecting said control office and all of said field stations, means at said control office for applying time spaced impulses to said communicating circuit throughout a cycle of operation, circuit means at each of said field stations operable to exclude more remote field stations from said communicating circuit during such cycle of operation initiated from that particular station, and current limiting means selectively introducible in the remaining portion of said communicating circuit at that particular station which initiated that cycle of operation, said means being effective during the application of each time spaced impulse on said communicating circuit during such cycle, whereby that station which initiated a cycle of operation can be identified in said control office.
11. In a centralized traffic controlling system for railroads, a control office, a plurality of field stations, a communicating circuit extending from said control office to the several field stations, means at said control office for applying time-spaced impulses to said communicating circuit, impulse selecting means at said control office operable to determine the resistance of said communicating circuit preceding the application of each time-spaced impulse thereof in accordance with preselected code calls, and station selecting means at each field station selectively responsive to said code calls for selecting the particular one of said field stations corresponding to the particular code call transmitted.
12. In a centralized traffic controlling system for railroads, a control office, a plurality of field stations, a communicating circuit extending from said control office to the several field stations and normally energized with a low degree of current from a source of energy at said control office, means at said control office for intermittently interrupting said communicating circuit, means at said control office for initiating operation of said communicating circuit interrupting means by applying a greater amount of current to said communicating circuit, and means at said field stations for initiating operation of said communicating circuit interrupting means by momentarily interrupting said communicating circuit.
13. In a centralized traffic controlling system for railroads, a control office, a plurality of field stations, a communicating circuit conductively connecting said control office to all of said field stations, impulsive means at said control office arranged to intermittently energize said communicating circuit a predetermined plural number of times in each cycle, means at said control office for selecting the amount of current of each of said communicating circuit impulses according to predetermined codes, and code responsive means at each field station arranged each to respond to a particular code to which no other field station will respond.
14. Code creating apparatus for creating codes of current impulses each code of which comprises a series of impulses of currents varying in strength comprising, a relay for intermittently at a certain rate energizing a control circuit, and a second relay for intermittently at a varying rate shunting a resistance in said control circuit.
15. Code creating apparatus for creating codes of current impulses each code of which comprises a series of impulses of currents varying in strength comprising, a relay for intermittently at a certain rate energizing a control circuit, and a second relay for intermittently at a varying rate shunting a resistance in said control circuit said second relay being picked up if energized by current of one polarity and being dropped if energized by current of the reversed polarity.
16. In combination, a circuit connecting a central office and a plurality of field stations said field stations being in series in said circuit, a line relay for each field station in said circuit, means for normally energizing said circuit by current of low intensity, means for impressing codes upon said circuit at said office and at each of said field stations, means responsive to energization of said circuit by current of high intensity to allow said office to impress a code of impulses on said circuit, and means responsive to deenergization of said circuit to allow a field station to impress a code of impulses upon said circuit.
17. In combination with a central office and a plurality of field stations, a relay at said central office and at each field station, a circuit including said relays in series, a lock relay at each field station for opening said circuit at such field station, a second relay at each field station for shunting said circuit toward the central office side of the point of opening at such field station, and a third relay for impressing a code of im-

pulses on said circuit when said lock relay and said second relay are in their operative conditions.

18. In combination with a central office and a plurality of field stations, a relay at said central office and at each field station, a circuit including said relays in series, a lock relay at each field station for opening said circuit at such field station, a second relay at each field station for shunting said circuit toward the central office 5 side of the point of opening at such field station, means for intermittently interrupting said circuit at said central office, and means for shunting and unshunting a resistance in said circuit at the field station where said lock relay and said second 10 relay are in their active conditions to cause the series of impulses to reflect a code at said central office.

19. In combination; a control circuit extending from a central office to a field station; a line relay in said control circuit; a series of neutral type stepping relays; and means for causing said stepping relays to be sequentially picked up one at a time and one for each deenergization of said control circuit including a half-step relay which has 25 a pick-up circuit, a holding circuit and buck-down stick circuit which circuits for said half-step relay are for picking up said half-step relay upon alternate energizations of said control circuit and dropping it on the remaining intermediate energizations of said control circuit.

20. In combination; a control circuit extending from a central office to a field station; a line relay in said control circuit; a series of neutral type stepping relays; and means for causing said stepping relays to be sequentially picked up one at a time and one for each deenergization of said control circuit including, a half-step relay which is picked up upon energization of its main winding and when once up is stuck up by a stick circuit including its own front contact, and is caused to assume its retracted position by energization of a second and opposing winding included in a circuit including its own front contact, for when assuming one position picking up an odd numbered stepping relay and when assuming its other position picking up an even numbered stepping relay; said half-step relay having its pick-up circuit closed upon one energization of said control circuit and having its bucking circuit closed upon the next energization of said control circuit.

21. A selector system for transmitting, by distinctive codes characterized by a series of impulses of large and small currents arranged in distinctive order, information from a distant field station to a central office comprising; a circuit connecting said office and field station, means at said office for closing and opening said circuit a predetermined number of times for each cycle of operation of said system, means at said field station for shunting and unshunting a resistance unit included in said circuit to characterize a code, and code responsive means at said central office responsive to a particular one of the codes so impressed on said circuit.

22. A selector system for transmitting, by distinctive codes characterized by a series of impulses of large and small currents arranged in distinctive order, information from a distant field station to a central office comprising; a circuit connecting said office and field station, means at said office for closing and opening said circuit a predetermined number of times for each cycle of operation of said system, means at said field station for shunting and unshunting a resistance

unit included in said circuit to characterize a code, and code responsive means at said central office responsive to the amount of current flowing during each current impulse to decipher the code of an entire cycle and operate an associated electro-responsive device only when such code is of a predetermined character. 5

23. In combination with a control office and a plurality of field stations, a line circuit extending from the control office through the several field stations, impulsing means at the control office for at times intermittently interrupting said line circuit, a resistor at each field station, a lock relay at each field station for opening said line circuit with respect to the more remote field stations and 10 for inserting said resistor at that station in said line circuit then including the less remote field stations, means at each field station for shunting and unshunting said resistor at that station in accordance with a predetermined code call when 15 said lock relay at that station is energized, means at each field station for at times energizing said lock relay at that station, said means being capable of being initially effective only when said line circuit is unaffected by said impulsing means, and 20 decoding means at said control office responsive to the distinctive changes in current values in said line circuit due to the shunting or unshunting of said resistors at a particular one of said field stations while said impulsing means is effective. 30

24. In combination with a control office and a field station, a normally energized line circuit, code transmitting apparatus at said control office and at said field station, means at said control office for initially increasing the current of said 35 line circuit when the code transmitting apparatus at said control office is to operate, means at said field station for initially opening said line circuit when the transmitting apparatus at the field station is to operate, and means at the control office 40 and at the field station for indicating the different initial line circuit conditions to thereby establish the direction of transmission so that only one code transmitting apparatus will operate 45 at any one time.

25. In a centralized traffic controlling system for railroads, a control office and a field station connected by a line circuit, a marginal relay and a sensitive relay connected to said line circuit at said station, impulsing means at said office for 50 applying a series of characteristic impulses to said line circuit, means responsive to said impulses for selectively energizing said marginal and sensitive relays, a normally inactive code forming means at said station, a lockout relay at said station, 55 means responsive to the selective energization of said marginal and sensitive relays for operating said lockout relay, and means responsive to the operation of said lockout relay for rendering said code forming means active. 60

26. In an impulse transmitting system, a loop impulse transmitting circuit, means at one end of said loop circuit for generating and transmitting time spaced impulses of invariable polarity over 65 said circuit, and code transmitting means at the other end of said loop circuit for varying the intensity of selected ones of said impulses to form codes.

27. In an impulse transmitting system, a loop 70 impulse transmitting circuit, means at one end of said loop circuit for generating and transmitting time spaced impulses of invariable polarity over said circuit, code transmitting means at both ends of said loop circuit for varying the intensity 75

- sity of selected ones of said impulses to form codes, and means allowing only one of said code transmitting means to operate at the same time.
28. In combination; a line circuit having a series of distinctive current conditions existent therein which conditions are inter-spaced by de-energized conditions; a series of stepping relays; means for causing said stepping relays to be picked up sequentially, only one for each of said deenergized conditions; a plurality of local channel circuits sequentially closed by said stepping relays, one for each stepping relay; and electro-responsive means controlled over each channel circuit in accordance with the particular distinctive current condition of said line circuit following the picking up of a stepping relay.
29. In a remote control system, a line circuit connecting a control office and a field station, a source of current for energizing said line circuit, impulsive means in the control office only for intermittently opening and closing said line circuit, step-by-step means in the control office and at the field station operated synchronously to take one step for each deenergization of said line circuit, a plurality of devices at the field station, transmitting means at the field station effective on each step of said step-by-step means to distinctively vary the energized condition of said line circuit in accordance with the condition of one of said devices, and receiving means at the control office effective on each step of said station by step-by-step means to register the distinctive energized condition of said line circuit for that step.
30. In a remote control system, a line circuit connecting a control office and a field station, a source of current for energizing said line circuit, impulsive means in the control office only for intermittently opening and closing said line circuit, step-by-step means in the control office and at the field station operated synchronously to take one step for each deenergization of said line circuit, a device at the field station for each step, transmitting means at the field station effective on each step of said step-by-step means to distinctively vary the energized condition of said line circuit in accordance with the condition of said device for that step, an indication device at the control office for each step, receiving means at the control office responsive to each distinctive energized condition of said line circuit, and circuit means controlled by said receiving means on each step to control said indication device for that step in accordance with the distinctive energized condition of said line circuit.
31. In a remote control system for transmitting indications from a field station to a control office over a line circuit, means at the control office including a battery source for intermittently energizing and deenergizing said line circuit, step-by-step means in the control office and at the field station operated synchronously to take one step upon each deenergization of said line circuit, means at the field station governed by its step-by-step means and effective to distinctively vary the energized condition of said line circuit for each step in accordance with the indications to be transmitted, an indication device in the control office for each step, and means in the control office distinctively responsive to the variations in the energized conditions of said line circuit and effective on each step of said step-by-step means to position said indication device for that step in accordance with the distinctive variation for that step.
32. In a remote control system, a line circuit connecting a control office and a field station, means wholly in said control office for closing and opening said line circuit for impressing thereon measured time spaced impulses of current, transmitting means at said station for selectively conditioning said line circuit at that station during each open condition of said line circuit so as to cause a distinctive energized condition upon the next closure of said line circuit in said central office, and means in said central office distinctively responsive to each of said distinctive current conditions, whereby indications are transmitted from the field station to the central office with the successive impulses wholly measured in the control office.
33. In combination; a control relay operated to opposite positions alternately for a plurality of times in succession; a plurality of stepping relays; a single neutral half-step relay; pick up circuits for said half-step relay, each including a contact of said control relay in one of its positions, and said circuits respectively closed through front contacts of alternate stepping relays; pick up circuits for said stepping relays, each including a contact of said control relay in its other position and a front contact of the preceding stepping relay, and said pick up circuits for alternate stepping relays including a front contact of said half-step relay with the remaining including a back contact of said half-step relay; and a stick circuit for said neutral half-step relay closed when it is picked up on a particular step and maintained closed until the next stepping relay is picked up and said control relay contacts are again in said one position.
34. In combination; a line circuit having a series of time spaced impulses applied thereto; a control relay responsive to each successive impulses of said series to thereby be picked up for each impulse and to be dropped for each time space; a cycle demarking relay responsive to said time spaced impulses so as to be picked up at the beginning of said series and dropped at the end of said series; a series of stepping relays; a single neutral half-step relay; pick up circuits for said half-step relay, each including a front contact of said control relay, and said circuits respectively closed through front contacts of alternate stepping relays; pick up circuits for said stepping relays, each including a back contact of said control relay and a front contact of the preceding stepping relay, and said pick up circuits for alternate stepping relays including a front contact of said half-step relay with the pick up circuits for the intermediate relays including a back contact of said half-step relay; stick circuits for said stepping relays including a front contact of said cycle demarking relay; and stick circuit means for said neutral half-step relay closed when said half-step relay is picked up on a particular step and maintained closed until the next stepping relay is picked up and until said control relay is again picked up.
35. In a remote control system; a line circuit connecting a control office and a field station; a source of current for energizing said line circuit; impulsive means in the control office only for intermittently opening and closing said line circuit; step-by-step means in the control office and at the field station operated synchronously to take one step for each deenergization of said line circuit; a plurality of control levers at the control office, one for each step; transmitting means at the control office effective on each step

of said step-by-step means to characteristically control the condition of the line circuit so as to cause a distinctive energization of the line circuit upon the next closure thereof in accordance with 5 the position of said control lever for that step; a plurality of indication devices at the field station, one for each step; receiving means at the field station responsive to each distinctive energization of said line circuit; and means controlled 10 by said receiving means on each step to control said device for that step in accordance with the following distinctive energization of said line circuit.

36. In combination, a line circuit having a 15 series of time spaced impulses applied thereto; a control relay having contacts operated to opposite positions alternately in response to said series of impulses and time spaces; a plurality of stepping relays; a half-step relay having contacts 20 operable to either of two opposite positions; means causing said half-step relay to actuate its contacts to an opposite position each time the contacts of said control relay assume one of their positions; a pick-up circuit for each odd stepping 25 relay, except the first, including a front contact of the preceding even stepping relay, a back contact of the succeeding even stepping relay, a contact of said half-step relay in one of its positions and a contact of said control relay in its 30 other position; a pick-up circuit for each even stepping relay, except the last, including a front contact of the preceding odd stepping relay, a back contact of the succeeding odd stepping relay, said contact of said half-step relay in the other 35 of its positions, and said contact of said control relay in its other position; and stick circuits for said stepping relays maintained closed until all of said stepping relays are picked up.

37. In combination; a line circuit having a 40 series of time spaced impulses applied thereto, a relay repeating said impulses so as to be picked up for each of said impulses and dropped for each of said time spaces; a cycle demarking relay responsive to said impulses so as to be picked up 45 at the beginning of said series and dropped at the end of said series; a bank of stepping relays; a pick-up circuit for each of said stepping relays and each including a front contact of the next preceding relay, said pick-up circuits being divided into two groups, namely, those for the odd 50 numbered relays and those for the even numbered relays; means for successively energizing said pick-up circuits, only one upon alternate operations of said repeating relay and alternately 55 a pick-up circuit for said odd and even groups; stick circuits for each of said stepping relays; and means including said cycle demarking relay for energizing said stick circuits until all of said stepping relays are picked up.

60. 38. In combination; a line circuit having a series of time spaced impulses applied thereto; a neutral control relay responsive to each successive impulse of said series to thereby be picked up for each impulse and to be dropped for each 65 time space; a cycle demarking relay responsive to said time spaced impulses so as to be picked up at the beginning of said series and dropped at the end of said series; a series of stepping relays; a single half-step relay for said series of 70 stepping relays and provided with contacts operable to either of two opposite positions, means including said series of stepping relays for causing said half-step relay to actuate its contacts to opposite positions each time said control relay 75 is picked up; a pick up circuit for each odd step-

ping relay including a front contact of the preceding stepping relay, except the first, a contact of said half-step relay in one of its positions and a contact of said control relay closed when it is dropped away; a pick-up circuit for each even stepping relay including a front contact of the preceding stepping relay, a contact of said half-step relay in the other of its positions and a contact of said control relay closed when it is dropped away; and a stick circuit for each of said stepping 10 relays including a front contact of said cycle demarking relay, said stick circuits being closed until all of said stepping relays of said series are picked up. 5

39. In combination, a line circuit having a 15 series of time spaced impulses impressed thereon, a control relay for repeating each of said impulses and each of said time spaces, a slow acting relay picked up at the beginning of said series and dropped at the end of said series, a 20 plurality of stepping relays having pick-up circuits each including a front contact of the next preceding stepping relay, a half-step relay for alternately preparing the pick-up circuits of the odd numbered and even 25 numbered stepping relays, means including said control relay for actuating said half-step relay to an opposite position in response to each impulse on said line circuit, means including said control relay and said half-step relay 30 for energizing the pick-up circuits of said stepping relays sequentially, one for each time space on said line circuit, and stick circuits for said stepping relays including a front contact on said slow acting relay. 35

40. In a remote control system, a line circuit having a series of time spaced impulses of selected characters impressed thereon, a plurality of stepping relays and a single half-step relay, means responsive to each time space between successive 40 impulses of a series for causing a separate one of said stepping relays to operate, means responsive to alternate impulses of a series for causing said half-step relay to operate, means controlled by said half-step relay and an operated stepping 45 relay for selecting the circuit of the next stepping relay to be operated, means responsive to the operation of said stepping relays for sequentially preparing a series of local channel circuits, a series of devices associated with said channel 50 circuits, and means responsive to said impulses for governing each of said devices in accordance with the character of the next impulse impressed on said line circuit following the operation of each stepping relay. 55

41. In a remote control system, a line circuit having a series of time spaced impulses of selected characters impressed thereon, a line relay in said circuit responsive to all impulses of said series irrespective of their character, a plurality 60 of stepping relays and a single half step relay, means including said line relay effective for each time space between successive impulses of said series for causing a separate one of said stepping relays to operate, means including said line 65 relay effective for alternate impulses of a series for causing said half-step relay to operate, means controlled by said half-step relay and an operated stepping relay for selecting the circuit of the next stepping relay to be operated, means responsive to the operation of said stepping relays for sequentially preparing a series of local channel circuits, a series of devices respectively associated with said channel circuits, and means responsive to each of said impulses on said line circuit for 70 75

distinctively operating that one of said devices in accordance with the character of the such impulse through the medium of that one of said channel circuits closed by the operation of the 5 stepping relay for the preceding time space.

42. In a remote control system, a line circuit having a series of time spaced distinctive impulses on said line circuit, a plurality of stepping relays and a single half step relay, means responsive to each time space between successive impulses of a series for causing a separate one of said stepping relays to operate, means responsive to each impulse of a series for causing said half-step relay to be actuated to an opposite position, means controlled by said half-step relay and an operated stepping relay for selecting the circuit of the next stepping relay to be operated, means responsive to the operation of said stepping relays for sequentially preparing a series of 10 local channel circuits, and means responsive to the next impulse following each operation of a stepping relay for selectively energizing said channel circuit closed by that stepping relay.

43. In a remote control system, a station, a line circuit having a series of time spaced distinctive impulses on such line circuit, a line relay at said station distinctively responsive to all impulses of a series on said line circuit, a plurality of stepping relays and a single half-step relay at said

station, means responsive to each time space between successive impulses of a series for causing a separate one of said stepping relays to operate, means responsive to each impulse of a series for causing said half-step relay to be actuated to an 5 opposite position, means controlled by said half-step relay and an operated stepping relay for selecting the circuit of the next stepping relay to be operated, means responsive to the operation of said stepping relays for sequentially closing a 10 series of local channel circuits, and means controlled by the distinctive response of said line relay following each operation of a stepping relay for energizing a channel circuit closed by the preceding stepping relay. 15

44. In a remote control system of the selector type; the combination with a control office and a field station; of a single line circuit connecting said control office with said field station; impulsive means only at said control office for energizing said line circuit with a plurality of impulses; code controlling means at said control office and at said field station for determining the character of said impulses, whereby messages are transmitted over said line circuit to and 20 from said field station to said control office; and means allowing only one code controlling means to be effective at any one time. 25

CHARLES S. BUSHNELL.
